UNITED STATES PATENT OFFICE.

KURT KARL FRIEDRICH, OF ANNABERG IM ERZGEBIRGE, GERMANY.

COLLAPSIBLE LANTERN.

Application filed March 10, 1926, Serial No. 93,637, and in Germany May 23, 1925.

My invention relates to illumination devices and more especially to a lantern having the form of a star. It is an object of my invention to provide a lantern of this kind which can be folded, to reduce the cost of packing and shipping, in substantially the same manner as the well known bellows-shaped Chinese lanterns.

I achieve this by composing the lantern of a plurality of rows of hollow pyramids, preferably of square cross-section, each pyramid constituting one of the rays of the star and being formed of triangular pieces of paper, cardboard, wood or the like, joined together in a foldable manner so that each pyramid can be folded down. The pyramids of each row are foldably joined by their adjoining edges and each row of pyramids can therefore be formed into a circular girdle of rays. Two superposed rows of pyramids are also foldably joined by their adjoining edges so that all the rows of pyramids form a single coherent collapsible body.

I further provide means for uniting the free ends of each row when unfolding the lantern, and for causing part of the pyramids or rows of pyramids to assume a position enclosing a pointed angle with the adjacent pyramid or row of pyramids.

Some of these means will be fully described with reference to the accompanying drawing forming part of this specification and illustrating a lantern embodying my invention by way of example.

In the drawings—

Fig. 1 is a perspective view of the unfolded lantern ready for use, while

Fig. 2 shows the same in substantially folded condition ready for packing and shipping.

Fig. 3 is an end view showing the rows of pyramids as viewed from their bases, the pyramids being unfolded but not yet shaped into circular girdles of rays.

Fig. 4 is a perspective view illustrating the way in which the rows of pyramids shown in Fig. 3 are converted into circular girdles of rays.

Fig. 5 illustrates the way in which the bottom ray is mounted, while

Fig. 6 discloses the manner of mounting and fixing the top ray.

Referring to the drawing, Fig. 1 shows the star-shaped lantern to be composed of a great number of square pyramids a , and Fig.

3 shows how these pyramids are arranged in three rows, each comprising eight pyramids a^1 and a frustum of a square pyramid b at the end of each row, this frustum serving for uniting the ends of the rows when forming the star.

Fig. 3 further shows that in the top and bottom rows the outer triangular part of each alternate pyramid is formed with a diagonal fold allowing this part to be folded inwards so that the pyramids provided with the folds a^2 can easily be transformed into triangular pyramids for the purpose hereinafter described.

It is further shown in Fig. 3 that to the free bottom edge of the fifth pyramid from the right in the top and bottom rows is joined a separate pyramid, the one marked g being designed to form the bottom ray of the star and having joined to its free edges frusta f of square pyramids, adapted to be inserted in other pyramids of the same row. The separate pyramid i joined to the free edge of the fifth pyramid from the right in the bottom row is unfolded entirely. To the free edges of the first, third, fifth and seventh pyramid from the right in the bottom row are foldably joined flaps l , a string d is attached to the outer end of each flap l and strings h are also attached in the bottom corners of those parts of the pyramids of the outer rows which are divided by the diagonal folds a^2 .

If it is desired to unfold the structure and to form it into a lantern enclosing an electric lamp, the folded rows of pyramids shown in Fig. 2 are first unfolded so as to present the end view shown in Fig. 3. The three superposed rows of pyramids are now formed into so many substantially circular girdles of pyramids, as shown in Fig. 4 and the frustum b of a pyramid at the end of each row is inserted in the pyramid a^1 at the other end of the same row. Now the bottom pyramid g is placed in position at right angles to the adjoining row of pyramids a^1 , the frusta f being inserted in the pyramids a^1 of this row. Now the two strings h of each pyramid of the row adjoining the bottom row g provided with a diagonal fold a^2 are united into a loop and these pyramids are thereby imparted triangular shape, whereby this row of pyramids is reduced in diameter on its outside and is thereby forced to assume a position at a pointed angle to the middle row, as is shown in Fig. 6, where

the structure is shown in upright position with the bottom pyramid *g* pointed downwards. In this position of the structure the incandescent lamp suspended from its conductors is introduced into the lantern and the top ray or pyramid *i* is now folded around the flaps *l*, the strings *d* projecting from the point of the pyramid *i*, as shown in Fig. 1 and serving for suspending the lantern.

Obviously the invention is not restricted to the particular form of the star shown in the drawings, nor to a star composed of or containing square pyramids, and I wish it to be understood that I do not desire to be limited to the exact details of construction shown and described, for obvious modifications will occur to a person skilled in the art.

20 I claim:—

1. Foldable illumination lantern comprising two rows of foldable pyramids, the pyramids in each row being foldably joined by their adjoining edges and the two rows being joined by their common edge, a frustum of a pyramid at one end of each row and a foldable pyramid foldably joined to the free edge of one pyramid of each row.

2. Foldable illumination lantern comprising two rows of foldable square pyramids, the pyramids in each row being foldably joined by their adjoining edges and the two rows being joined by their common edge, a frustum of a pyramid at one end of each row and a foldably square pyramid foldably joined to the free edge of one pyramid of each row.

3. Foldable illumination lantern comprising two rows of foldable square pyramids, the pyramids in each row being foldably joined by their adjoining edges and the two rows being joined by their common edge, a frustum of a pyramid at one end of each

row and a foldable square pyramid foldably joined to the free edge of one pyramid of each row, one side of each alternate pyramid in each row having a middle fold allowing said pyramid to be formed into a triangular pyramid.

4. Foldable illumination lantern comprising three rows of foldable square pyramids, adjoining rows and adjoining pyramids in each row being foldably joined by their adjoining edges, a foldable square pyramid foldably joined to one edge of a pyramid of each outer row and means for uniting the pyramids at the ends of each row and for fastening the free edges of the two pyramids joined to the outer rows.

5. Foldable illumination lantern comprising three rows of foldable square pyramids, adjoining rows and adjoining pyramids in each row being foldably joined by their adjoining edges, a foldable square pyramid foldably joined to one edge of a pyramid of each outer row and means for uniting the pyramids at the ends of each row and for fastening the free edges of the two pyramids joined to the outer rows, one side of each alternate pyramid in each outer row having a middle fold and a pair of strings allowing said pyramid to be formed into a triangular pyramid.

6. Foldable illumination lantern comprising two rows of foldable pyramids, the pyramids in each row being foldably joined by their adjoining edges and the two rows being joined by their common edge, a frustum of a pyramid at one end of each row, a foldable pyramid foldably joined to the free edge of one pyramid of each row and a flap at the free edge of some pyramid of an outer row.

In testimony whereof I affix my signature.

KURT KARL FRIEDRICH.
